UNITED STATES PATENT OFFICE

PETER LE ROY GOUDIE, OF JOHNSON COUNTY, KANSAS

DESIGN FOR AN AWNING SHEET

Application filed March 28, 1932. Serial No. 43,312. Term of patent 3½ years.

To all whom it may concern:

Be it known that PETER LE ROY GOUDIE, citizen of the United States of America, and resident in the county of Johnson and State of Kansas, has invented a new, original, and ornamental Design for an Awning Sheet, of which the following is a specification, reference being had to the accompanying drawing, forming part thereof, in which, the figure is a plan view of an awning sheet, showing my design. The edge of the awning sheet opposite to the scalloped border is plain as shown.

I claim:

The ornamental design for an awning sheet, as shown, substantially as described.

Dated March, 1932.

PETER LE ROY GOUDIE.
